MEDICAL STATION INSTRUMENT UNIT

Paul A. Lyons, La Jolla, and Nathaniel W. Burks, Jr.,
and David L. Britt, San Diego, Calif., assignors to
Medical Instruments & Technology Corp., San Diego,
Calif.

Filed Oct. 20, 1972, Ser. No. 299,230

Term of patent 14 years

Int. Cl. D24—01

U.S. Cl. D83—1 F

Fig. 1

Fig. 2

Fig. 3

Fig. 4

FIG. 1 is a perspective view of a medical station instrument unit, showing our new design.

FIG. 2 is a rear elevational view thereof.

FIG. 3 is a front perspective of a modified embodiment of the instrument unit illustrated in FIG. 1; and

FIG. 4 is a top plan view thereof, the bottom plan view being similar.

We claim:

The ornamental design for a medical station instrument unit, substantially as shown and described.
